UNITED STATES PATENT OFFICE

155,475

DESIGN FOR AN ELECTRIC HAIR DRIER

Richard F. Berndt, Plainfield, N. J., assignor, by
mesne assignments, to John Oster Manufacturing
Company, Racine, Wis., a corporation of
Wisconsin

Application December 26, 1947, Serial No. 143,340

Term of patent 14 years

(Cl. D86—10)

To all whom it may concern:

Be it known that I, Richard F. Berndt, a citizen of the United States and resident of Plainfield, in the county of Union and State of New Jersey, have invented a new, original, and ornamental Design for an Electric Hair Drier, of which the following is a specification, reference being had to the accompanying drawing, forming part thereof.

In the drawing:

Figure 1 is a side elevational view of the electric hair drier showing my new design;

Figure 2 is a front elevational view; and
Figure 3 is a rear elevational view.

I claim:

The ornamental design for an electric hair drier, as shown.

RICHARD F. BERNDT.
